FORMING PILES

Filed Dec. 9, 1922

UNITED STATES PATENT OFFICE

JOHN B. GOLDSBOROUGH, OF CROTON-ON-HUDSON, NEW YORK

FORMING PILES

Application filed December 9, 1929. Serial No. 605,828.

This invention relates to the formation of piles, particularly of the type consisting of a metallic tube or shell embedded in the ground and filled with concrete or other 5 foundation material.

In some cases the shells for piles of this character are driven with the lower end open, but in such cases it is necessary to clear out the shell in order that it may be filled with 10 foundation material. This clearing operation is expensive and causes a delay in the preparation of the foundations for the building to be subsequently erected.

In order to avoid the disadvantages attending the driving of shells in open condition various forms of driving points for closing the lower ends of the shells have been proposed and some have been used. These driving points are usually of heavy cast iron, 20 are expensive to manufacture and must be produced in as many sizes as there are diameters of shells. It is usually necessary to order them sometime in advance of the time when they will be required, in order that they 25 may be on hand when needed to avoid any delay in preparing the foundations. A further disadvantage of the use of such driving points is the reduced load value of the piles with which they are associated, when they 30 are driven to rock, due to the relatively small area of contact between the driving point and the rock, this reduction amounting in some cases to as much as two-thirds of the bearing value which the pile would have if 35 the area of its entire lower end were in contact with the rock.

Another method which is frequently used for avoiding the necessity for clearing out the shells after they have been sunk is to 40 employ a spud or plunger substantially filling the shell and having a pointed lower end projecting beyond the bottom of the shell. The use of a spud or plunger is attended with difficulties when employed for sinking open 45 ended shells in wet ground, for the suction

effect caused by the removal of the spud or plunger results in the shell being more or less filled with earth and water after the spud or plunger has been removed. The shell cannot satisfactorily be filled with concrete 50 under such conditions.

The use of a spud or plunger for sinking a shell is attended with a further disadvantage due to the increased headroom required to insert the spud within the shell before the 55 latter is driven into the ground due to the fact that it is necessary to lift the spud above the top of the shell in order to drop it into the latter.

This invention has for its general object 60 the avoidance of the disadvantages of prior methods of forming piles of the general character referred to above, as well as the simplification and lessening of the cost of forming such piles. These and other objects of the 65 invention are attained by closing the lower end of the shell with a flat cap preparatory to sinking it and by performing the sinking operation without the use of a spud or plunger, thereby keeping the shell clear and 70 eliminating the necessity for providing the extra head-room which is required when shells are sunk by means of spuds placed within them. This reduction of the headroom is of particular advantage, as the cost 75 and difficulty of handling driving apparatus increases greatly if the height of the apparatus is increased above that required for sinking shells of ordinary length by a driving device acting directly upon the top of 80 the shell without the use of a spud.

After the shell has been sunk in the ground in the manner above described, the concrete is poured into the shell to form a cased shell, or the driving form or shell may be removed 85 in the manner well known to those skilled in the art.

The caps for closing the lower ends of the shells may be formed of sheet metal which is cheap and easily obtainable and they may be 90

formed by unskilled labor at the location where the piles are being sunk, thereby avoiding the necessity for ordering in advance, as is required in the case of specially constructed driving points, as well as considerably reducing the cost of the operations. Since the caps may be formed as required for the particular sizes of pipes which are being used as shells for the piles, the expense of carrying in stock a number of different sizes, as is necessary in the case of driving points, is avoided.

The present improvement is also particularly adapted for use in cases in which a bulb 15 is to be formed at the lower end of the pile by expelling successive charges of material from the shell until a bulb of the required size has been produced. The initial charge of material as it is expelled from the shell carries 20 with it the cap which remains permanently embedded below the bulb to reinforce the footing of the latter.

The facility with which a shell provided with a flat closure for its lower end may be 25 driven into the ground appears to be due in large measure to the formation below the closure of a cone-like mass of closely compacted soil which acts as a driving point thereby facilitating the penetration of the shell into the ground in a manner analogous 30 to that which occurs when a heavy metallic driving point is employed.

The particular nature of the invention as well as other objects and advantages thereof 35 will appear more clearly from a description of certain preferred embodiments as shown in the accompanying drawings in which—

Fig. 1 is a side elevation, showing pile-driving apparatus about to sink a pile tube.

Fig. 2 is an enlarged view in vertical section, showing a pile tube about to be sunk by my improved method;

Fig. 3 is a similar view, showing the pile tube in its course of descent into the earth;

Fig. 4 is a vertical section, disclosing the sunken pile tube, a bulb-foot-forming charge being shown at the bottom of the tube and about to be acted upon by a rammer;

Fig. 5 is a like view, but depicting the condition after the rammer has acted;

Fig. 6 shows a concrete pile with a bulb footing formed by the action of the rammer on repeated concrete charges;

Fig. 7 is another vertical section showing the pile tube and its bottom cap driven to a sub strata of rock;

Fig. 8 illustrates the pile driven into rock of a type which it may penetrate; and

Fig. 9 is a further enlarged view, showing 60 in perspective the bottom portion of the pile tube with its cap in place.

Referring to the drawing, there is shown in Fig. 1, a metallic tube or shell 1 placed in position with respect to pile-driving apparatus 2 to be driven into the ground by a

hammer 3 of such apparatus. Closing the lower end of the pile shell 1 is a cap 4 having properties peculiarly suiting it to facilitate the advance of the pile shell through the earth. As shown in Figs. 2 and 9, the cap 70 has a flat web circumscribed by an upturned flange 5 adapted to fit around the bottom of the shell 1.

By reason of the fact that the upturned flange encloses the lower end of the driving 75 form or shell, the penetrating head is of greater area than that of the lower end of the driving form, thereby providing a footing of larger area for the pile than that of the lower end of the driving form or shell, or the concrete body thereof. Such enlargement of the head also enables the driving form or shell to be more readily removed if it is desired to provide an uncased pile.

Temporarily placed on the upper end of 85 the shell 1 is an impact ring 6 for directly receiving the blows of the hammer 3, this ring being removed after the pile has been sunk to the desired depth, but in the meantime preserving the upper end of the shell from deformation.

With my improved method of pile construction, I may use pile driving apparatus of considerably smaller size, as shown in Fig. 1, whereas when a plunger or spud 7 is employed 95 much enlarged pile-driving apparatus is necessitated.

Not only does the improved method disclosed herein make it possible to use less expensive pile-driving apparatus, but a correspondingly advantageous saving in the employment of labor is effected. With the avoidance of the use of a plunger or spud for driving the shell 1 there is also an accompanying saving of time.

An enlarged view, principally in section, of the pile shell 1, as it is positioned for entry in the ground, is shown in Fig. 2, wherein the flat bottomed cap 5 is in place on the bottom of the shell 1, the impact ring 6 surmounts the top of the shell and the hammer 3 is about to strike a blow. The repeated blows of the hammer force the shell 1 into the ground, and displace the earth.

The flat bottomed cap 4 prevents entry of the earth into the interior of the shell 1, and, at the same time, due to its shape accumulates earth on its under side. With the downward movement of the pile shell 1, the adjacent earth partly moves laterally away from the shell and relatively upward thereto, the earth directly beneath the cap 4 becoming under compression and reacting against the flat under surface of the cap. In consequence, an inverted cone of packed earth forms on the under side of the cap 4, as shown at 8 in Fig. 3, and is that residuum of displaced earth that fails to escape from beneath the pile shell and its bottom cap. This self-generated packed earth cone becomes more solid 130

from the force used in the driving operations and serves as a driving point to aid in penetrating the earth of less cohesion, which must be displaced for the reception of the pile.

5 After the shell has been driven into the ground to the desired depth it may be filled with suitable foundation material, such as concrete, either plain or reinforced. It is frequently necessary to provide enlarged 10 footings for the piles. In such cases a bulb of desired proportions on the lower end of each pile admirably supplies such footing.

It is, therefore, proposed in such cases to deposit a charge of concrete in the hollow 15 shell 1, after it has been sunk, and to enter the shell with a plunger or spud 7, as shown in Fig. 4. To do this requires no larger sized pile-driving apparatus. The plunger 7 is raised and dropped, forcing off the bottom 20 cap 4 and expelling the concrete charge from the bottom of the shell 1, as illustrated in Fig. 5. Thereafter, the plunger is withdrawn and an additional charge inserted in the shell 1, after which the plunger is re-entered and 25 dropped to expel the last concrete charge. This operation is performed as many times as there are number of charges of concrete required for a bulb of given proportions.

The bulb 9 is thus formed, the driven-off 30 cap reenforcing it. The still empty shell is then filled with concrete, resulting in a pile substantially like that shown in Fig. 6.

Inasmuch as subterranean conditions are 35 unlike in different places, it becomes necessary, in driving piles, to successfully contend with the varying difficulties presented, which has not always been of simple solution. For example, when the usual heavy cast metal driving point is used on the lower end of a 40 pile tube or shell, and the pile is driven to rock, only the point at the lower end of the pile bears on the rock, as indicated by dotted lines at 10, in Fig. 7. As previously indicated, the pile, under these conditions, some- 45 times has its load value depreciated as much as two-thirds, and in municipalities and other rigidly regulated communities, where the authorities insistently require a generous factor of safety, piles merely having a point 50 bearing on rock must either be used in excessive numbers, adding greatly to the cost, or the edifice they support must be undesirably limited in size and as to its loads.

In Fig. 7, my improved pile is shown as 55 having been driven to rock, and clearly illustrates how, with its flat-bottomed cap, there is secured to the finished pile its maximum permissible load. Since the flat bottomed cap is relatively thin, any upwardly 60 extending projection of the rock that may be under it will, in conjunction with the heavy hammer blows, deform the cap sufficiently to permit a substantially perfect seating of the pile. This will be readily un- 65 derstood in view of the light metal that can

be used in making the bottom cap 4, such a cap having been used, in one instance, which was made of material of a thickness less than 1/150th of the diameter of the pile shell. Such a cap on the lower end of a pile shell, 70 which was driven by a steam hammer showed no sign of rupture. Encountering unyielding rock, however, and being subjected to heavy hammer blows, the thin cap 4 will obviously conform itself to the obstruction, 75 and allow the pile as an entity to secure an entirely satisfactory seat.

In the case of the pile shell 1, fitted with its bottom cap 4, being driven to rock which may be penetrated, and it being desired to consolidate the pile and the rock, the pile-driving apparatus may be used to cause the shell or tube 1 to make an incision and entry into the rock for a suitable distance, as shown in Fig. 8. Under these circumstances, the 80 lower annular edge of the shell 1 will shear off the flange 5 of the bottom cap 4 from the web or central main portion of the latter, after which the shell will be driven in the rock, thus to be anchored therein. The 85 empty shell 1 is then filled with concrete.

From the foregoing it is apparent that I have devised a concrete pile and a method of forming it, that, while being simple has improved efficiency, and eliminates the cost of 90 excavating the interior of the pile shell after it has been driven. It is equally clear that I have produced a concrete pile that avoids the need for a heavy cast driving point which in turn dispenses with the need of patterns 95 for forming such cast points, saving the expense of them and also the time needed to construct them and to mold the driving points. There stands forth markedly the further advantage of being able to construct 100 the bottom caps for the pile shells in the field, in sizes to suit any of varying requirements, by unskilled labor, and from material substantially universally obtainable.

105 By means of the invention a construction 110 chamber may be formed, extending to a firm bearing of sufficient area to give high load capacities to the foundation material which is subsequently placed in the chamber. Such a result cannot be obtained with driving 115 points, particularly when the latter are sunk to rock or other hard surfaces on account of the low bearing value of the points.

Moreover, since the bottom cap is fashioned 120 so as to act as a buckle plate and to generate a natural driving point, and suits itself automatically to subterranean conditions without special attention of the workmen, and is subject to an automatic dispensing of 125 itself when a shell is to be driven into rock, it is manifest that in a simple manner, I have produced a pile suitable for very general use, at a low cost, and one possessed of very high efficiency.

130 While certain preferred embodiments of

the invention have been shown and described, it will be understood that various changes may be made therein without departing from the principle of the invention as described in the appended claims.

5 I claim:—

1. The method of forming a pile which consists in preliminarily closing the lower end of a tubular shell with a flat cap formed of relatively thin metal, driving the closed shell into the ground, depositing charges of foundation material in the shell and expelling them therefrom to drive off and flatten the cap beneath the extended footing formed by the expelled charges of concrete whereby the cap serves as a reinforcement below the footing and filling the shell with foundation material.
- 10 2. An apparatus for forming concrete piles in the ground comprising only a tubular driving form, a detachable, substantially flat, infrangible metallic penetrating head engaged only by the lower end of said tubular driving form, and means for preventing lateral displacement of said head from the lower end of said driving form during the driving thereof.
- 15 3. An apparatus for forming concrete piles in the ground comprising only a tubular driving form, a substantially flat infrangible metallic penetrating head of substantially uniform thickness and of greater area than that of the lower end of said driving form detachably engaging and closing said lower end and having means presenting a shoulder operable to prevent lateral displacement of said head from the lower end of said driving form during the driving thereof.
- 20 4. An apparatus for forming concrete piles in the ground comprising only a tubular driving form, a substantially flat infrangible metallic penetrating head of substantially uniform thickness detachably engaging and closing the lower end of said driving form and having a flange surrounding said lower end.
- 25 5. An apparatus for forming concrete piles in the ground comprising a metallic tubular driving form, a substantially flat infrangible metallic penetrating head of greater area than that of said driving form detachably engaging and closing the lower end of said driving form and having a peripheral flange surrounding said lower end.
- 30 6. An apparatus for forming concrete piles in the ground comprising a cylindrical driving form, a substantially flat infrangible metallic penetrating head, of greater area than that of the lower end of said driving form and of less thickness than the thickness of the wall of said driving form, engaging the lower end of said driving form and having a peripheral flange enclosing said lower end.
- 35 7. The method of forming a concrete pile which comprises driving into the ground a hollow driving form having at its lower end

a detachable, substantially flat, infrangible metallic penetrating head of greater area than the area of the lower end of said driving form, and producing a relative movement between the head and the driving form to provide a permanent metallic footing for the concrete body of the pile.

70 In testimony whereof I affix my signature.
JOHN B. GOLDSBOROUGH.
